UNITED STATES PATENT OFFICE.

SAMUEL L. COLES, OF ST. LOUIS COUNTY, MISSOURI.

DESIGN FOR A TOY VEHICLE.

53,291.

Specification for Design.

Patented May 13, 1919.

Application filed March 15, 1918. Serial No. 222,743. Term of patent 7 years.

To all whom it may concern:

Be it known that I, SAMUEL L. COLES, a citizen of the United States, residing at St. Louis County, State of Missouri, have invented a new, original, and ornamental Design for Toy Vehicles, of which the following is a specification, reference being had to the accompanying drawing, forming a part thereof.

Figure 1 is a side elevation of a toy vehicle, showing my new design;

Copies of this patent may be obtained for five cents each, by addressing the "Commissioner of Patents, Washington, D. C."

Fig. 2 is a front elevation.

Fig. 3 is a top plan view.

I claim:

The ornamental design for a toy vehicle, as shown.
